WALTER H. WHEELER, JR., AND JACOB W. OGDEN, OF STAMFORD, CONNECTICUT, AS
SIGNORS TO PITNEY-BOWES POSTAGE METER CO., OF STAMFORD, CONNECTICUT,
A CORPORATION OF DELAWARE.

POSTMARKING AND STAMP-CANCELING MACHINE.

Application filed December 21, 1925. Serial No. 76,657.

This invention is an improvement in machines for postmarking and canceling mail matter, and is particularly designed for use as a manually operated or hand power machine, although adapted to be operated by power if desired.

The object of the invention is to provide a machine very simple in construction, accurate in operation, and capacitated to handle a large variety of first class mail matter of great variety of kinds and sizes, such as is commonly found in the ordinary run of first class mail.

Further objects are to provide a novel feed hopper by which letters are prevented from becoming wedged together at the point where they are passed from the hopper to the printing devices, to provide novel means by which the delivery of the letters is synchronized with the revolutions of the printing die, and novel letter arresting devices whereby they are properly timed and spaced apart in the operation of the machine on mixed mail matter. Various other novel features and advantages of the machine will be hereinafter pointed out.

In the accompanying drawings we have illustrated one practical embodiment of the invention, and will describe the same with reference thereto, and summarize in the claims the essentials of the invention and the novel combinations of parts and novel features of construction for which protection is desired.

35 In said drawings—

Figure 1 is a front elevation of a complete machine.

Figure 2 is a somewhat enlarged side elevation of the feed end of the complete machine.

Figure 3 is an enlarged detail sectional view.

Figure 4 is a somewhat enlarged sectional view.

45 In the embodiment of the invention illustrated in the drawings, the operative parts are mounted upon a supporting plate 1 which is preferably slightly inclined from the perpendicular, and is attached to a base 1^a which may be mounted upon a stand or other support of any suitable construction,

not shown. The supporting plate 1 is provided with bearings 1^b for a shaft 2^s having on its front end a hand wheel 2 provided with a crank handle 2^h by which it 55 may be rotated. A fly wheel 2^u is mounted on the rear end of the shaft 2^s to impart momentum and unity of operation to the operative parts and this fly wheel 2^u may be used as a belt wheel if it is desired to drive 60 the machine by power by belting wheel 2^u to an electric motor or other suitable prime mover.

Above the shaft 2^s the plate 1 is provided with bearings 1^c for a shaft 3^s carrying a 65 printing cylinder 3. Motion may be transmitted from the shaft 2^s to the shaft 3^s by means of gears 2^t and 3^t on the shafts 2^s, 3^s as shown. The cylinder 3 preferably has a portion 3^m of its surface provided with 70 an engraved plate adapted to print the cancellation marks omitted and is also provided with a movable engraved die 3^p omitted to print the postmark. These features being common in postmarking machines it is not 75 deemed necessary to illustrate or describe same in detail.

Cooperating with the cylinder 3, and arranged beneath the same, is an impression roller 4 which is mounted eccentrically of 80 the feed wheel 2 upon a stud shaft 4^s attached to a swinging or yielding member 5 which is shown as pivoted on a stud 5^a fastened to the plate 1. The impression roller should be held in yielding contact with the 85 impression cylinder 3, by suitable means; a spring 5^t being indicated in the drawings. Said impression roller is driven by frictional contact with the printing cylinder or the mail matter which is passed between 90 the impression roller and printing cylinder. A suitable stop should be provided to limit the upward travel of this member 5 and impression roller 9 to prevent the latter from entering the gaps 3^b in the surfaces of the 95 printing cylinder, an adjustable stop bolt 5^a attached to plate 1 being shown.

The engraved canceling bars, and the lettering and type on the postmarking die, are preferably arranged in straight lines on the 100 periphery of the cylinder, and at right angles to the axis of said cylinder. The pe-

riphery of the impression roller 4 is provided with alternating grooves and projections so disposed relative to the lines of lettering and canceling bars of the printing cylinder that the letters and bars of the die will be opposite the grooves of the impression roller, and the projecting rings of the impression roller will be opposite the spaces between the lines of letters and bars. With this construction there is no actual contact between the engraved portion of the die and the impression roller, but as the projecting portions of each are allowed to enter the mating grooves to an appreciable extent, a thin piece of paper passed between them will be sufficiently tensed to receive an imprint from the inked engraving. This arrangement is broadly old in the art and therefore need not be further described or shown in detail.

The periphery of the printing cylinder 3 is provided at opposite sides with annular friction bands 3^a. These bands may be made of soft leather, rubber or suitable material that will frictionally grip the surface of the mail matter and assist in forwarding it through the machine. Preferably these bands do not extend entirely around the cylinder, but are gapped as shown at 3^b in Figures 1 and 3, for a purpose hereinafter explained.

The impression roller 4 is provided with peripheral end portions 4^a adapted to register with the friction bands 3^a of the printing cylinder to cooperate therewith in forwarding the mail; and portions 4^a may be also provided with frictional surfaces like bands 3^a if desired.

In operation, when the hand wheel 2 is revolved, both the printing cylinder 3 and impression roller 4 will revolve; and the momentum of the impression roller 4 will carry it past the gaps 3^b in the printing cylinder 3, and the rotation will be practically continuous.

The printing surfaces of the roller 3 may be inked by any suitable means. As shown an ink roller 6 having an absorbent body charged with ink is adjustably mounted over the printing die 3, and supplies ink to the printing surfaces of the cylinder.

The mail—such as letters or envelopes—is fed from a feed hopper at one side of the cylinder 3. As shown the feed hopper comprises a back plate 12 fastened to the plate 11; and a bottom plate 11, and inner wall plate 7 adjacent the cylinder 3. The plates 7 and plate 11 are preferably made of sheet steel and fastened to the plate 12, as indicated in the drawings. The wall 7 is approximately vertically disposed, and is adjacent the left hand periphery of the cylinder 3, and projects above the printing cylinder 3.

The end wall 7 is provided with a slot 7^a

in its front end, in which slot is a metal strip 10, the upper end of which is pivoted at 10^a to the wall 7, and to this strip 10 is preferably adjustably attached a wiper 10^b by means of a clamp screw 10^c.

The outer surface of the strip 10 is preferably flush with the outer surface of the wall 7, and strip 10 hinged for convenience in fixing and adjusting the wiper 10^b. The strip 10 cannot be swung toward the printing cylinder beyond the position shown in Figure 1; but it may be swung outwardly as far as need be to facilitate the adjustment of the wiper.

Adjacent the outer end of the cylinder 3 is a plate or casting 8 which is supported by and between the wall 7 and a bracket 9 attached to the plate 12.

The upper part of wall 7 may be let into or bent around the adjacent end of plate 8, so as not to hinder the free passage of the mail.

An arm or lever 13 is pivoted at 13^a to the inner side of the plate 8, as shown in Figures 1 and 3, and this arm is normally held in lifted position by means of a spring 13^b. The arm is provided with a lug 13^c on its inner side adapted to be engaged by a cam 16 attached to the shaft 3^c on the adjacent end of the printing member 3; the lever 13 and the cam 16 being arranged in the space between the plate 8 and the outer end of printing cylinder 3. Mounted on the free end of arm 13 is a stop 14 which is preferably attached to the lower end of a rod 14^a which is supported by and endwise movable on the arm 13 and is normally depressed by a spring 14^b. When the arm 13 is depressed by the cam, as shown in Figures 1 and 3, stop 14 projects across the path of the letter in position to arrest the feeding movement of the letters.

The arm 13 is moved up (by spring 13^b) and down by the cam 16, once during each revolution of the printing cylinder; and the stop 14 is thus moved into and out of the letter path once for every revolution of the printing cylinder. If the stop 14 on returning to position across the letter path should engage with the tail end of a moving letter, it will yield or give back until the letter has passed, but, under the influence of the spring 14^b, will immediately block the letter path after such letter has passed. The stop 14 can yield easily if it contacts with a passing letter, as described, but will not yield to force in the direction of the path of the letters because the angle on which the rod 14^a slides is nearly at right angles to that force.

The end of the floor 11 of the feed hopper is cut out or slotted slightly to accommodate the stop 14 in its operative position. The point where the stop 14 crosses the letter path is but a short distance in advance of

the bite of the printing and impression rollers. The wiper 10^b rests upon that part of the floor 11, immediately in front of the stop 14, its extreme end nearly touching the stop. This position of the wiper holds the letter firmly against the stop and prevents it from being curled upward and having its edge marred in case the push of the feed pads is too strong.

10 The hand wheel 2 is provided with one or more feed pads 2^r, spaced apart a distance equal to the circumference of the cylinder 3. The number of the feed pads 2^r employed depends upon the ratio of revolutions between the hand wheel 2 and the cylinder 3.

15 Each feed pad 2^r consists preferably of a plate or boss 2^p, attached to the rear side of the hand wheel, and covered by a rubber band. The projecting end of each pad is 20 adapted to engage and forward the lowermost piece of mail in the feed hopper as the hand wheel is revolved. The feed pads 2^r on the hand wheel 2 will move in orbits eccentric to the impression roller 4, and the 25 feed pads are timed to carry letters of the poorest feeding quality up to the stop. Letters of a better feeding quality may arrive at the stop sooner, but in either case the stop will release them at the right moment.

30 In the machine shown the printing cylinder 3 is adapted to make two revolutions for each revolution of the hand wheel 2; therefore the hand wheel 2 has two feed pads 2^r, 180° apart, and makes one revolution for two of the printing cylinders; there 35 is therefore a definitely fixed time relation between the action of the feed pads and the action of the printing cylinder. If all the mail matter were of a uniform character this 40 relation of feed pads to die would be sufficient to insure that the imprint would be made in the same position on every piece of mail. But as the mail is not uniform, the stop 14 is provided, to arrest and hold back 45 each letter until the proper time and to then release it, as described.

50 If the friction bands 3^a on the printing cylinder 3 were continuous a bulky piece of mail might be caught in the bite between the printing cylinder and impression roller before the stop 14 had properly released it and to prevent this the gaps 3^b are left in the bands 3^a. The engraved part of the printing cylinder immediately following the 55 gap will pinch the letter against the impression roller shortly after the stop is released.

55 The floor 11 of the feed hopper is of novel and peculiar construction. From its outer end, at the left, it first slants downwardly toward the hand wheel and then curves upward following approximately the curve of the rim of the wheel. This curved portion of the bottom plate is slotted as at 11°, to 60 admit the passage of the feeding pads 2^r.

One part of the floor 11 extends below and another part extends above the path of the feed pads 2^r, and said parts support the mail in the hopper until the feed pad lifts it forward. The wiper 10^b is pressed toward 70 that part of the floor 11 which extends above the path of the feed pads, and will rub against the passing mail and prevent more than one piece passing at a time.

Owing to the peculiar shape of the floor 75 11 short pieces of mail will slant away from the wall 7 at a more pronounced angle than long mail. This feature adds to the efficiency of the feed, short mail being generally harder to separate than long, because as 80 a rule it runs thinner, post cards for instance being very hard to feed because they pack together so tightly. The slant of the floor makes the separation of the mail easier as 85 the thin pieces of mail will not become wedged under the wiper and the upper pieces have a tendency to slide away from the wall 7.

Each feed pad 2^r will act on the lowermost piece of mail up to the point where it 90 passes the stop 14, although its action begins to diminish in force at a point just a short distance ahead of the stop, at which point the curve of the floor ceases to parallel that of the path of the pads and becomes tangent 95 to the arc.

The pivot 13^a is the center of the arc of travel of the stop 14 in relation to the cam 16, and the rod 14^a arranged at such an angle that the stop when down will positively prevent the passage of a letter, but will quickly move out of the way when it is released by the cam; and yet can easily yield on its return trip until the released piece of mail has 100 passed.

105 After the printing operation the letters are discharged into a suitable receiving hopper wherein they are stacked. The hopper shown is composed of a back plate 15, bottom 15^a, an adjustable outer end wall 15^b, and an inner guard wall 15^c. The back plate 15 is secured to the plate 1; and the floor 15^a may be either an integral part of, or fastened to, the plate 15; the wall 15^b is 110 preferably adjustably fastened to the floor 15^a in order to accommodate letters of different lengths; the guard 15^c is partly curved around the hand wheel to prevent letters rebounding from the end wall 15^b in contacting 115 with the hand wheel.

120 The angle of inclination and shape of the feed hopper floor, and the proximity of the feed pads to the stop, and the angle and construction of the stop are important features of the invention.

125 Heretofore in machines of this character the floor of the feed hopper has been either level, or in some cases inclined towards the point of delivery to assist the feed of mail by gravity. In such inclined gravitational feeds 130

cards or envelopes are apt to become wedged together so tightly that the wiper could not properly separate them, and two or more pieces of mail would pass at a time. In cases where the floor was level extra feeding means acting on the mail matter in advance of the separator was necessary; and this involved a more complicated construction.

10 In our invention the floor of the feed hopper is so shaped that the mail matter laid upon it has a slant away from the separator, so that gravity would tend to hinder the feed, and this prevents the aforesaid objectionable wedging effect. The curving of the bottom adjacent the rim of the wheel greatly increases the extent of arc of contact with the feed pads and obviates the necessity for auxiliary feeding means. Such long arc of contact makes it possible to feed pieces of mail whose forward edges are considerably back from the separator, a condition that often occurs in practice. The repeated impact of the feed pads at a point so far removed from the leading ends of the envelopes also tends to loosen up the pile and keep a film of air between the pieces of mail and makes their separation easy; and as the pile of mail is supported only at the ends, 20 there will be less squeezing out of the air from between the pieces.

What we claim is:

1. In a postmarking and stamp canceling machine of the character specified, a printing cylinder; an impression roller coacting therewith, a rotatable feed wheel, a separator; a feed hopper having a bottom plate adapted to support the mail matter and incline it by gravity away from the separator, 35 a stop to successively arrest the letters; a movable support for the stop, cam means for normally holding the stop in letter arresting position, means for withdrawing the stop from arresting position when permitted by the cam.

2. In a postmarking and stamp canceling machine of the character specified, a printing cylinder; an impression roller coacting therewith, a rotatable feed wheel, a separator, a feed hopper having a downwardly and upwardly inclined bottom plate adapted to support the letters and incline them by gravity away from the separator, a stop to successively arrest the letters, a movable support for the stop, cam means for normally holding the stop in letter arresting position, and means for withdrawing the stop from arresting position when permitted by the cam.

60 3. In a postmarking and stamp canceling machine of the character specified, a printing device; an impression device coacting therewith; a rotatable feed wheel, a separator; a feed hopper having a bottom plate adapted to support the letters at two points

and incline them by gravity away from the wiper, said bottom being curved adjacent the rim of the feed wheel to increase the extent of contact of the feed device with the letter.

4. In a postmarking and stamp canceling 70 machine of the character specified, a printing device; an impression roller coacting therewith; a rotatable feed wheel, having feed pads, and operating beside and eccentrically of the impression roller; a wiper; a feed hopper having a downwardly and upwardly inclined bottom plate adapted to support the letters at two points; said bottom being curved adjacent the rim of the feed wheel to increase the extent of contact 75 of the feed device with the letter.

5. In a postmarking and stamp canceling machine of the character specified, printing devices, and feed devices; a feed hopper having a bottom adapted to support the mail matter at two spaced points, leaving the matter unsupported at center whereby the weight of the mail matter causes it to sag and incline away from the feed devices thereby facilitating separation of the mail by the 80 feed devices.

6. In a postmarking and stamp canceling machine of the character specified, a printing device; an impression device coacting therewith; feed devices and a separator; of a 95 feed hopper having a downwardly and upwardly inclined bottom plate adapted to support the mail matter at two spaced points leaving the matter unsupported at center whereby the weight of the mail matter causes 100 it to sag and incline away from the separator thereby facilitating separation of the mail by the feed devices.

7. In a postmarking and stamp canceling 105 machine of the character specified, a printing device; an impression device coacting therewith; a rotatable feed wheel, having feed pads, and a wiper; of a feed hopper having a downwardly and upwardly inclined bottom plate adapted to support the mail matter at 110 two spaced points, leaving the matter unsupported at center whereby the weight of the mail matter causes it to sag and incline away from the wiper thereby facilitating separation of the mail by the feed devices, substantially as specified.

8. In a postmarking and stamp canceling machine of the character specified, a printing cylinder having gapped feed bands on its periphery; an impression roller coacting 120 therewith; a rotatable feed wheel; a wiper; a feed hopper; a stop to successively arrest the letters; a movable support for the stop; cam means for normally holding the stop in letter arresting position; and means for withdrawing the stop from arresting position when permitted by the cam.

9. In a postmarking and stamp canceling machine of the character specified; a printing cylinder having gapped feed bands on 125

its periphery; an impression roller having circumferential annular portions adapted to coact with the feed bands on the cylinder; a rotatable feed wheel; a wiper; a feed hopper; a stop to successively arrest the letters; a movable support for the stop; cam means for normally holding the stop in letter ar- resting position; and means for withdrawing the stop from arresting position when permitted by the cam. 10

In testimony that we claim the foregoing as our own, we affix our signatures.

W. H. WHEELER, JR.
JACOB W. OGDEN.
